UNITED STATES PATENT OFFICE

CHARLES ADLER, JR., OF BALTIMORE, MARYLAND

DESIGN FOR A TRAFFIC SIGNAL

Application filed May 25, 1932. Serial No. 43,896. Term of patent 14 years.

To all whom it may concern:

Be it known that I, CHARLES ADLER, JR., a citizen of the United States, residing at the city of Baltimore and State of Maryland, have invented a new, original, and ornamental Design for a Traffic Signal, of which the following is a specification, reference being had to the accompanying drawing, forming a part thereof.

Figure 1 is an elevation showing the cover glasses lined for color, and

Figure 2 is a vertical section.

The respective cover glasses are of different color; each glass as indicated by the lining will display different intensities of the same color.

I claim:

The ornamental design for a traffic signal as shown and described.

CHARLES ADLER, JR.
